[57] CLAIM

The ornamental design for an information guide display device, as shown and described.

DESCRIPTION

FIG. 1 is a front, top and right side perspective view of an information guide display device, showing our new design;

FIG. 2 is a front elevational view thereof;

FIG. 3 is a top plan view thereof;

FIG. 4 is a bottom plan view thereof;

FIG. 5 is a right side elevational view thereof; the opposite side being a mirror image thereof;

FIG. 6 is a rear elevational view thereof;

FIG. 7 is a front, top and right side perspective view of a second embodiment of the information guide display device;

FIG. 8 is a front elevational view thereof;

FIG. 9 is a top plan thereof;

FIG. 10 is a bottom plan view thereof;

FIG. 11 is a right side elevational view thereof; the opposite side being a mirror image thereof; and,

FIG. 12 is a rear elevational view thereof.
